COLLAPSIBLE CONTAINER OR THE LIKE

Alexander Pischke, Trail, British Columbia, Canada, assignor of one-third to David Chow, Trail, British Columbia, Canada

Application March 22, 1932, Serial No. 600,530

7 Claims. (Cl. 221—60)

My invention relates to collapsible containers and the like and particularly to a collapsible container or the like having automatic self-opening and closing means.

- 5 It is an important object of my invention to provide a collapsible tube or the like having a self-opening and closing means actuated through the agency of the fluid contents of the tube or the like being placed under pressure, whereby to permit the dispensing of the said contents from the tube or the like, and upon the dispensing of a certain portion of the contents and the release of the pressure, will automatically close and seal the tube.
- 15 It is also an important object of my invention to provide a device of this kind which is of more positive action than devices of this general type heretofore provided, which is of simple and inexpensive construction and may be installed in tubes having the conventional dispensing neck, without material alteration thereto, obviating the absolute necessity to provide a different than conventional dispensing neck structure on tubes and containers of this type.

- 25 Other objects and advantages of my invention will be apparent from a reading of the following description taken in connection with the drawing, wherein for purposes of illustration I have shown a preferred embodiment of the invention.

30 In the drawing:—

Figure 1 is a transverse vertical sectional view through a collapsible tube showing the self-closing and opening means in the closed position.

Figure 2 is a view similar to Figure 1 except that the self-opening and closing means is shown in the open position, and a certain portion of the contents of the tube is in process of being dispensed from the dispensing neck of the tube or the like.

40 Figure 3 is a top plan view of Figure 1.

Figure 4 is a horizontal sectional view taken approximately on the line 4—4 of Figure 1 looking downwardly in the direction of the arrows.

Referring in detail to the drawing, wherein like numerals refer to like parts throughout the same, the numeral 5 generally designates a conventional type of collapsible tube such as is commonly employed to contain and dispense tooth paste and shaving cream and the like which is provided with a dispensing neck 6. Though the dispensing neck may be cylindrical in form I prefer to construct the same in the form of a square tube.

Within the dispensing neck 6 and at one side 55 of the lower end portion thereof there is secured

by means 7 passing through the wall of the tube, a hinge means 8 to which is hinged the lower end of a generally square plate 9 which fits the insides of the dispensing neck 6 in such a manner as to prevent at all times the passage between it and the neck of the contents of the tube. The plate 9 is normally maintained in the closed angular position shown in Figure 1 by a coiled spring 10 of generally horizontal disposition which engages one side of the dispensing neck and the outer portion of the plate 9. It will be obvious that when the plate 9 is in the position shown in Figure 1 the contents 11 of the tube are securely sealed so as to prevent the ingress of air and other contaminating elements, which operate to deteriorate the contents of the tube.

Secured upon the upper end of the plate 9 is a cap member 12 of flat construction in the form of a square in the event that the dispensing tube 5 is formed square, and the cap 12 has a lug depending therefrom at one side which is connected to the upper end of the plate 9. It will be seen that in the closed position of the self-closing and opening means the portion 13 engages the upper part of the wall of the dispensing neck 6 so as to have a large bearing thereagainst.

It will be observed that the cap 12 when in the closed position overlies the upper edge of the dispensing neck 6, and the underside of the plate which forms the cap 12 is slightly concaved as indicated at 14. It will be observed that the portion 13 seats against the wall of the dispensing neck simultaneously or practically so with the seating of the cap upon the upper edge of the dispensing neck, by action of the spring 10 when pressure upon the contents of the tube is released.

As will be seen in Figure 2 the swinging movement of the plate 9 away from the side of the dispensing neck opposite its pivotal connection is automatically accomplished by exerting pressure upon the contents 11 of the tube 5 whereby to force a portion of said contents against the under face of the plate 9 with sufficient force to overcome the tension of the spring 10, whereupon the plate 9 will be moved out of the way as seen in Figure 2, so as to permit the discharge or dispensing from and through the dispensing neck 6 of the desired quantity of the contents 11 of the tube.

Due to the angular disposition and formation of the self-opening and closing means of the invention, release of pressure upon the contents of the tube 5 will permit comparatively rapid return of the self-closing and opening means, as it readily pinches and pushes the contents of the tube out of its way, without unduly packing the same.

or unnecessarily working against the remaining contents of the tube, and that in returning to the closed position this means acts cleanly and positively to prevent leakage of the contents of the tube or contamination thereof from outside sources. The plate 9 as already stated is given a close sliding fit with the interior of the dispensing neck 6 so as to prevent any of the contents of the tube working past and getting into the chamber formed behind the plate 9 and in which the spring 10 is located, as this would deteriorate the spring and cause an accumulation of material behind the plate so as to impede and hamper its smooth and satisfactory action.

15 Though I have shown and described a preferred embodiment of the invention, it is to be definitely understood that I do not desire to limit the application of the invention thereto, and any change or changes may be made in material and structure 20 and arrangement of parts consistent with the spirit of the invention and the scope of the subjoined claims.

What is claimed is:—

- 25 1. A closing device for the discharge neck of a collapsible container, said closing device comprising a plate swingably mounted at its lower end in the neck and extending beyond the outer end of the neck, spring means mounted within the neck between and in engagement with the swingable plate and the wall of the neck for normally swinging the plate to a closing position across the neck, a cover member carried by the outer end of the plate for abutting and closing the outer end of the neck when the plate is in closing position.
- 30 2. A closing device for the discharge neck of a collapsible container, said closing device comprising a plate swingably mounted at its lower end in the neck and extending beyond the outer end of the neck, spring means mounted within the neck between and in engagement with the swingable plate and the wall of the neck for normally swinging the plate to a closing position across the neck, a cover member carried by the outer end of the plate for abutting and closing the outer end of the neck when the plate is in closing position, said spring means being located between the part of the neck on which the plate is mounted and the adjacent side of the plate.
- 35 3. A closing device for the discharge neck of a collapsible container, said closing device comprising a plate swingably mounted at its lower end in the neck and extending beyond the outer end of the neck, spring means mounted within the neck between and in engagement with the swingable plate and the wall of the neck for normally swinging the plate to a closing position across the neck, a cover member carried by the outer end of the plate for abutting and closing the outer end of the neck when the plate is in closing position, said plate being joined to the cover member at one side thereof so that the cover member will assume an out-of-the-way position when the plate is in the open position to enable discharge of the contents of the container without obstruction by the cover member.

4. A closing device for the discharge neck of a collapsible container, said closing device comprising a plate swingably mounted at its inner end within the neck and having a portion extending outwardly beyond the outer end of the neck, 5 spring means mounted within the neck between and in engagement with the swingable plate and the wall of the neck for normally swinging the plate to a closing position across the neck, said portion comprising a cover member carried by the outer end of the plate for abutting and closing the outer end of the neck when the plate is in closing position, said plate having another portion near its outer end arranged to contact and lie along a considerable portion of the interior of the 10 discharge neck when the plate is in closed position.

5. In a collapsible dispensing tube having a discharge neck, closure means for the neck, said closure means comprising a swingable member mounted in the dispensing neck, a cap member carried by the swingable member and having a position outward of the dispensing neck and arranged to seat against and close the dispensing neck when the swingable member is in closed position, spring means mounted within the neck between and in engagement with the swingable member and the wall of the neck normally urging the closure member toward closed position, said closure means being movable to open position for 30 dispensing material from the discharge neck by exerting sufficient pressure upon the material in the tube and neck.

6. In a collapsible dispensing tube having a dispensing neck, a swingable closure member having 35 its inward end rockably mounted on the interior wall of the dispensing neck, spring means mounted within the neck between and in engagement with the swingable closure member and the wall of the neck for normally urging said closure member toward closed position across the neck, and a portion carried by the outer end of the closure member to cover and lie in close contact with the outer end of the dispensing neck when the closure member is in closed position, and arranged to have 45 a position remote from the outer end of the dispensing neck when the closure member is in open position.

7. In a collapsible dispensing tube having a dispensing neck, a swingable closure member having 50 its inward end rockably mounted on the interior wall of the dispensing neck, spring means mounted within the neck between and in engagement with the closure member and the wall of the neck for normally urging said closure member toward closed position across the neck, and a portion carried by the outer end of the closure member to cover and lie in close contact with the outer end of the dispensing neck when the closure member is in closed position, and arranged to have 55 a position remote from the outer end of the dispensing neck when the closure member is in open position, said portion comprising an angularly arranged plate.

ALEXANDER PISCHKE. 65
